(57) CLAIM

We claim the ornamental design for a golf club head attachment, as shown and described.

DESCRIPTION

FIG. 1 is a perspective view of a golf club head attachment, as viewed from the front, above and one side, according to one embodiment.

FIG. 2 is a front elevation view of the golf club head attachment of FIG. 1.

FIG. 3 is a rear elevation view of the golf club head attachment of FIG. 1.

FIG. 4 is a side elevation view of one side of the golf club head attachment of FIG. 1.

FIG. 5 is a side elevation view of the other side of the golf club head attachment of FIG. 1.

FIG. 6 is a top plan view of the golf club head attachment of FIG. 1; and,

FIG. 7 is a bottom plan view of the golf club head attachment of FIG. 1.

The dashed lines in the drawings are for illustrative purpose only and form no part of the claimed design.
